RETRIEVABLE FORMATION TESTER

Hugh E. Drake, Huntington Park, Calif.

Application March 19, 1940, Serial No. 324,809

12 Claims. (Cl. 255—1)

This invention relates to a retrievable formation tester, whereby the fluids, gases and the like in a well can be recovered and examined by means of a tester which is lowered into the drill pipe from the surface.

A feature of my invention is to provide a retrievable formation tester which is interchangeable with a core barrel.

An object of my invention is to provide a novel formation tester, which can be operated with the mud pumps under full pressure, and while the drill pipe is rotated.

Another object of my invention is to provide a novel formation tester, which can be left in the hole any reasonable length of time before or after the test.

Another feature of my invention is that my novel retrievable formation tester makes a test on the bottom of the hole and also recovers a sample of the fluid or gas or formation, or both, in the sand, which is to be tested.

Other objects, advantages and features of invention may appear from the accompanying drawing, the subjoined detailed description and the appended claims.

In the drawings:

Figure 1 is a diagrammatic, longitudinal, sectional view of my retrievable formation tester.

Figure 2 is a fragmentary, longitudinal, sectional view of the lower part of my retrievable formation tester.

Figure 3 is a fragmentary, longitudinal, sectional view of the upper part of the same.

Figure 4 is an enlarged fragmentary, longitudinal, sectional view of the upper part of my formation tester, and showing particularly the latching mechanism.

Figure 5 is a longitudinal, sectional view of the reciprocating piston.

Figure 6 is a side elevation of the cam which operates in conjunction with the reciprocating piston.

Figure 7 is a fragmentary, longitudinal, sectional view of the lower barrel portion of my retrievable formation tester.

Referring more particularly to the drawings, the numeral 1 indicates the drill pipe, which extends downwardly into the bored hole from the surface of the ground. A bit 2 is mounted on the lower end of the drill pipe, and this bit includes a plurality of fluid passages 3, which extend vertically through the bit. A central hole 4 is provided through the bit 2, and a portion of the retrievable formation tester extends through this hole, as will be further described.

A guard tube 5 is fixedly attached to the bit 2 and rises in the drill pipe 1, a sufficient distance to entirely receive the retrievable formation tester 6. A latch head 7 is mounted on the upper end of the guard tube 5, and receives the latching member at the top of the formation tester, as will be further described. The guard tube 5 is spaced from the inner wall of the drill pipe to provide a fluid passage 8, through which the downwardly moving drilling mud passes. The drilling mud then is forced outwardly through the passages 3, and past an opening 9 in the bit, creating a partial vacuum within the guard tube 5. The reason for this evacuation on the inside of the guard tube is to relieve a back pressure on top of any material which may enter the formation tester from the bottom, as will be evident from the subsequent description.

The formation tester 6 comprises a latching sleeve 10, which includes a plurality of latching fingers 11, which are pivotally attached to the head adjacent their lower ends, as shown at 12. The cable attachment pin 13 has a limited vertical movement in the sleeve 10. A horizontal pin 14 on the lower end of the cable attaching pin 13 extends into vertical slots 15 in the fingers 11, and consequently upward movement of the cable attaching pin 13 will draw the fingers 11 inwardly, and out of slots 16, thus releasing the formation tester when it is desired to draw the same to the surface. Gravity or other means will cause the fingers 11 to drop into the position shown in Figure 4, and will cause these fingers to latch and hold the formation tester against accidental longitudinal movement.

A long barrel 17 is attached to the lower end of the latching sleeve 10, and this barrel retains the liquid or gas which may be recovered in the well. The barrel 17, as well as the lower portion 40 of the formation tester, fits loosely within the guard tube 5, and in order that drilling fluid may be prevented from passing downwardly between the formation tester and the guard tube, I provide a floating ring 18. This floating ring rests 45 against a seat 19 in the latch head 7. A rubber ring 20 bears against the floating seating ring 18, and yieldably presses the ring against its seat. The ring 18 is mounted between the latching sleeve 10 and the upper face of a valve control socket 21. The valve control socket is threaded onto the lower end of the latching sleeve 10, substantially as shown in Figure 4. The static pressure of the drilling mud in the drill pipe will be exerted against the seating ring 18, thus pressing 50 this ring tightly against its seat. Any misalign-

ment of the formation tester or lateral movement of the same in the guard sleeve 5 will not unseat the ring 18, and thus the drilling mud will be prevented from passing downwardly into the guard sleeve and around the barrel 17.

A cylinder 22 is threadedly attached to the lower end of the barrel 17 and an outer pipe 23 is threadedly attached to the lower end of the cylinder, and extends downwardly through the hole 4 and protrudes from the bit 2 a substantial distance, as shown in Figure 2. The lower end of the pipe 23 may be tapered, as shown at 24, so that when the pipe is forced downwardly into the formation to be tested, this taper will assist in packing off the formation so that oil, gas, and the like will be forced upwardly into the tube instead of passing around on the outside of the same. Rotation of the tool in the well will also cause the lower end of the pipe to "burn" or pack the formation, thus further insuring the proper operation of the tool insofar as the upward flow of material in the formation is concerned.

A sleeve 25 is mounted within the pipe 23, and seats against the lower tapered end of this pipe, as shown at 26. A coil spring 27 presses against the top of the sleeve 25, urging the sleeve downwardly against its seat 26. A cam stud 28 screws into the top of the sleeve 25, and is provided with a suitable annular cam 29 on the top thereof for the purpose of actuating the vacuum piston, as 30 will be further described. Spring core fingers 30, within the sleeve 25, engage the core, which passes upwardly into the sleeve for the purpose of holding this core against downward movement once it has entered the sleeve. The cam stud 28 is 35 mounted in the cylinder 22 on anti-friction bearings 31 so that the cam stud will readily rotate with the sleeve 25 when a core enters the sleeve and is engaged by the fingers 30.

A vacuum piston 32 is reciprocally and non-rotatably mounted in the cylinder 22. The pin 33, which extends through a slot 34 in the piston, holds said piston against rotation. A cam surface 35 on the bottom of the piston is engaged by the cam 29 of the stud 28, causing the piston to be reciprocated as the piston is rotated, and while the cam stud is held against rotation because of the core which has entered the sleeve 25. A suitable check valve 36 is provided on top of the piston 32. A coil spring 37 bears against the top of the piston 32, and against a head 38 of the cylinder, thus yieldably pressing the piston 32 downwardly, and causing reciprocation of this piston as it is rotated relative to the cam stud 28, as described above. A second check valve 39 may be provided in the head 38 for the purpose of trapping fluid above the head 38 and within the barrel 17.

A light check valve 40, above the valve 39, is normally held open by the load of the liquid in the barrel 17. On the upper end of the barrel 17, there is mounted a hollow valve post 41 on the upper end of which a valve plug 42 is mounted. Radial ports 43 in the member 42 are closed by the valve sleeve 44 when the tool is being run into the hole. The sleeve 44 is pressed upwardly by the coil spring 45, and has a limited vertical movement. The valve plug 42 is provided with coarse external threads, which mesh with internal threads in the lower end of the 70 socket 21, as shown at 46. When the tool is being run into the hole, the parts are in the position shown in Figure 3, and with the ports 43 closed, as shown. When the tool is at bottom, the barrel 17 and post 41, as well as the plug 42, 75

are held stationary and rotation of the drill pipe will cause the threads 46 to engage, thus moving the plug 42 upwardly off of its seat, until the top of the plug bears against the bottom of the socket 21, after which a driving action occurs through the post 41 and thence to the barrel 17. With the port 43 open, fluid in the barrel 17 can be forced outwardly ahead of oil, gas or the like which may be entering the formation tester from the bottom.

The operation of my formation tester is as follows:

In operation, the drill pipe 1 is already in the hole, with the bit 2 mounted on the lower end thereof, and with the guard tube 5 rising into the drill pipe and having the latch head 7 on the upper end thereof, as previously described. The retrievable formation tester is now lowered into the hole on a suitable cable, which is attached to the pin 13, or dropped into the hole. The valve plug 42 is closed and in the position shown in Figure 3. When the formation tester reaches bottom, the latch fingers 11 spring outwardly into the openings in the latch head, thus holding the formation tester against accidental longitudinal movement. The ring 18 rests on its seat 19 to prevent drilling mud from passing around the outside of the formation tester. The drill pipe is now lowered, and the outer pipe 23 is spudded into the formation, thus holding this pipe against rotation. However, this action only occurs during the first part of the operation.

Since the pipe 23 is held against rotation, the cylinder 22 and the barrel 17 are also held against rotation, and, therefore, the post 41 and the valve plug 42 will also be held stationary. Rotation of the drill pipe at this time will also rotate the guard tube 5 and, therefore, the latch head 7 and the socket 21. The threads 46 will now be engaged, which moves the plug 42 upwardly until this valve plug seats in the socket 21. As soon as the plug 42 is seated, the entire formation tester will rotate with the drill pipe.

The portion of the formation tester which protrudes below the bit 2 then advances into the formation, causing a core to be cut, which moves upwardly into the core sleeve 25 and is held by the spring fingers 30. Since the core is attached to the formation and consequently will not rotate, the sleeve 25 will also be held stationary, including the cam stud 28. Since the cam stud 28 is stationary and the piston 32 is revolving, the co-acting cam surfaces 29 and 35 will cause this piston to reciprocate, thus creating a partial vacuum within the formation tester, tending to pump material upwardly in the formation tester, and eventually into the barrel 17. The coil spring 27 permits the sleeve 25 to move vertically a small amount. Consequently the core entering the sleeve can push this sleeve upwardly under certain conditions, thus imparting a greater stroke to the piston 32 due to the fact that the cam surfaces 29 and 35 are more closely engaged, and consequently a greater stroke is imposed by the cam. This pumping action continues to force liquid and gas into the barrel 17, where it is trapped by the check valves 36 and 39.

While the drill pipe is thus rotating and operating, the formation tester, drilling mud is circulating downwardly through the drill pipe and through the passage 8, thus creating partial vacuum in the orifice 9 and, therefore, within the guard tube 5. Thus partial vacuum acts through the ports 43 (which are now open), thus relieving a part of the static pressure on top of the

barrel 17, which permits the fluid from the formation to enter this barrel more readily.

The formation tester can be retrieved at any time by pulling the supporting cable upwardly. This releases the latch fingers 11 and the entire formation tester is elevated to the surface. This can be done without removing the drill pipe and the drilling bit.

Having described my invention, I claim:

1. A retrievable formation tester adapted to be mounted in drill pipe comprising means releasably securing the formation tester in the drill pipe, a pump piston reciprocally mounted in the formation tester, and means to reciprocate said piston on rotation of the drill pipe.

2. A retrievable formation tester adapted to be operated in drill pipe comprising means releasably holding the formation tester in the drill pipe, a guard tube fixedly mounted in the drill pipe, the formation tester extending through the guard tube, a sealing ring movably mounted on the formation tester, a seat in the guard ring on which the ring rests, a pump piston reciprocally mounted in the formation tester, and means to reciprocate said piston on rotation of the drill pipe.

3. A retrievable formation tester adapted to be mounted in drill pipe, a guard tube fixedly mounted in the drill pipe at the lower end thereof, latch means on the formation tester engaging the guard tube whereby the formation tester is removably held in operative position, a pipe on the lower end of the formation tester, said pipe extending below the drill pipe and adapted to extend into the formation, a sleeve rotatably mounted in said pipe, core engaging means in the sleeve, a pump piston, means connecting the sleeve and the piston whereby the piston is reciprocated on relative rotation of the sleeve and said pipe, said pump piston being adapted and arranged to force fluid into the upper portion of the formation tester.

4. A retrievable formation tester adapted to be mounted in drill pipe, a guard tube fixedly mounted in the drill pipe at the lower end thereof, latch means on the formation tester engaging the guard tube whereby the formation tester is removably held in operative position, a pipe on the lower end of the formation tester, said pipe extending below the drill pipe and adapted to extend into the formation, a sleeve rotatably mounted in said pipe, core engaging means in the sleeve, a pump piston, means connecting the sleeve and the piston whereby the piston is reciprocated on relative rotation of the sleeve and said pipe, said pump piston being adapted and arranged to force fluid into the upper portion of the formation tester, a sealing ring yieldably mounted on the formation tester adjacent the upper end thereof, and a seat in the guard tube upon which the sealing ring rests.

5. A retrievable formation tester adapted to be operated in drill pipe, having a bit at the lower end thereof, a guard tube fixedly mounted within the drill pipe, comprising a barrel, latch means on the upper end of the barrel engageable with the guard tube whereby the formation tester is releasably held in the drill pipe, a post fixedly mounted on the upper end of the barrel, an externally threaded plug on the post, said plug having by-pass ports therein extending to the outside thereof and giving access to the inside of the guard tube, an internally threaded socket on the upper end of the formation tester,

said socket being adapted to screw onto the said plug and lift the plug off of its seat on relative rotation of the socket and plug.

6. A retrievable formation tester adapted to be operated in drill pipe, having a bit at the lower end thereof, a guard tube fixedly mounted within the drill pipe, comprising a barrel, latch means on the upper end of the barrel engageable with the guard tube whereby the formation tester is releasably held in the drill pipe, a post fixedly mounted on the upper end of the barrel, an externally threaded plug on the post, said plug having by-pass ports therein extending to the outside thereof and giving access to the inside of the guard tube, an internally threaded socket on the upper end of the formation tester, said socket being adapted to screw onto the said plug and lift the plug off of its seat on relative rotation of the socket and plug, a pump piston reciprocally mounted in the formation tester, and means to reciprocate said piston on rotation of the drill pipe.

7. A retrievable formation tester adapted to be operated in drill pipe, having a bit at the lower end thereof, a guard tube fixedly mounted within the drill pipe, comprising a barrel, latch means on the upper end of the barrel engageable with the guard tube whereby the formation tester is releasably held in the drill pipe, a post fixedly mounted on the upper end of the barrel, an externally threaded plug on the post, said plug having by-pass ports therein extending to the outside thereof and giving access to the inside of the guard tube, an internally threaded socket on the upper end of the formation tester, said socket being adapted to screw onto the said plug and lift the plug off of its seat on relative rotation of the socket and plug, a sealing ring yieldably mounted on the formation tester adjacent the upper end thereof, and a seat in the guard tube adjacent the upper end thereof on which the ring rests.

8. A retrievable formation tester adapted to be operated in drill pipe, having a bit at the lower end thereof, a guard tube fixedly mounted within the drill pipe, comprising a barrel, latch means on the upper end of the barrel engageable with the guard tube whereby the formation tester is releasably held in the drill pipe, a post fixedly mounted on the upper end of the barrel, an externally threaded plug on the post, said plug having by-pass ports therein extending to the outside thereof and giving access to the inside of the guard tube, an internally threaded socket on the upper end of the formation tester, said socket being adapted to screw onto the said plug and lift the plug off of its seat on relative rotation of the socket and plug, a pump piston reciprocally mounted in the formation tester, and means to reciprocate said piston on rotation of the drill pipe, a sealing ring yieldably mounted on the formation tester adjacent the upper end thereof, and a seat in the guard tube adjacent the upper end thereof on which the ring rests.

9. A retrievable formation tester adapted to be operated in drill pipe, a bit on the lower end of the drill pipe, a guard tube fixedly mounted within the drill pipe, a latch head on the guard tube, said formation tester comprising latching means adapted to engage the latch head, a barrel, the lower portion of said barrel extending through the bit, a sleeve rotatably mounted in the lower portion of the barrel, core engaging means in the sleeve, a cam stub rising from the sleeve, said cam stub having a cam surface on the

upper face thereof, a pump piston reciprocally mounted above the cam stud, the cam surface on the cam stud engaging the piston to reciprocate the same on relative rotation of the piston and the cam stud, and check valves in the barrel above the piston.

10. A retrievable formation tester adapted to be operated in drill pipe, a bit on the lower end of the drill pipe, a guard tube fixedly mounted in the drill pipe and spaced from the inner wall of said drill pipe, said bit having circulation holes extending therethrough, said bit having an opening therein extending from the circulation holes to the inside of the guard tube, said formation tester comprising an elongated barrel loosely mounted in the guard tube and extending through said tube, latch means connecting the formation tester and the guard tube whereby the formation tester is releasably held in the guard tube, a sealing ring yieldably mounted on the formation tester adjacent the top thereof, a seat in the guard tube upon which the sealing ring rests, a hollow post rising from the barrel, a valve plug on the upper end of the post, said valve plug having ports extending to the outside thereof, a seat in the guard tube on which the valve plug normally rests, means to unseat the valve plug on relative rotation of the guard tube and barrel of the formation tester.

11. A retrievable formation tester adapted to be operated in drill pipe, a bit on the lower end of the drill pipe, a guard tube fixedly mounted in the drill pipe and spaced from the inner wall of said drill pipe, said bit having circulation holes extending therethrough, said bit having an opening therein extending from the circulation holes to the inside of the guard tube, said formation

tester comprising an elongated barrel loosely mounted in the guard tube and extending through said tube, latch means connecting the formation tester and the guard tube whereby the formation tester is releasably held in the guard tube, a sealing ring yieldably mounted on the formation tester adjacent the top thereof, a seat in the guard tube upon which the sealing ring rests, a hollow post rising from the barrel, a valve plug on the upper end of the post, said valve plug having ports extending to the outside thereof, a seat in the guard tube on which the valve plug normally rests, means to unseat the valve plug on relative rotation of the guard tube and barrel of the formation tester, pump means in the formation tester, and means to actuate the pump means on rotation of the drill pipe.

12. A retrievable formation tester adapted to be operated in drill pipe, a bit on the lower end of the drill pipe, a guard tube fixedly mounted in the drill pipe and spaced from the inner wall of said drill pipe, said bit having circulation holes extending therethrough, said bit having an opening therein extending from the circulation holes to the inside of the guard tube, said formation tester comprising an elongated barrel loosely mounted in the guard tube and extending through said tube, latch means connecting the formation tester and the guard tube whereby the formation tester is releasably held in the guard tube, a sealing ring yieldably mounted on the formation tester adjacent the top thereof, a seat in the guard tube upon which the sealing ring rests, pump means in the formation tester, and means to actuate the pump means on rotation of the drill pipe.

HUGH E. DRAKE.
